(57) **CLAIM**

I claim the ornamental design for an aquaponic tank, as shown and described.

DESCRIPTION

FIG. 1 is a front isometric view of the aquaponic tank.

FIG. 2 is a front elevational view of the aquaponic tank. The left, right, and rear elevational views are the same.

FIG. 3 is a top plan view of the aquaponic tank; and, FIG. 4 is a bottom plan view of the aquaponic tank.

The surface shading in FIGS. 1-4 shows contour of the three-dimensional aspects of the design. The features shown in broken lines form no part of the claimed design. The two stacked funnel components are removable from the tank.
